United States Patent Office

Des. 232,644
Patented Sept. 3, 1974

232,644

AUTOMOTIVE VEHICLE KEY SAFE

Iral D. Barrett, P.O. Box 3167, Salem, Oreg. 97302

Filed Jan. 8, 1973, Ser. No. 322,087

Term of patent 14 years

Int. Cl. D3—02

U.S. Cl. D31—22

FIG. 1

FIG. 2

FIG. 3

FIG. 4

FIG. 5

FIG. 1 is a front elevational view of an automotive vehicle key safe showing my new design;

FIG. 2 is a rear elevational view;

FIG. 3 is a right side elevational view;

FIG. 4 is a left side elevational view; and

FIG. 5 is a top plan view.

I claim:

The ornamental design for a automotive vehicle key safe, as shown and described.
